(57) **CLAIM**

The ornamental design for a surge protector as shown and described.

DESCRIPTION

FIG. 1 is a front elevation view of a surge protector showing my new design;

FIG. 2 is a rear elevation view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and,

FIG. 8 is a perspective view thereof.

The broken lines in the drawings are for the purpose of illustrating portions of the surge protector that form no part of the claimed design.

1 Claim, 4 Drawing Sheets
